FLUID FUEL BURNER CONTROL SYSTEM

Carl G. Kronmiller, Minneapolis, Minn., assignor
to Minneapolis-Honeywell Regulator Company,
Minneapolis, Minn., a corporation of Delaware

Application April 15, 1936, Serial No. 74,481

1 Claim. (Cl. 236—21)

My invention relates to a fluid fuel burner control system and more particularly to such a system wherein the flow of fuel to the main burner is controlled by a valve actuated by a pressure motor.

In systems of this type it is the usual practice to provide one or more control or pilot valves which regulate the pressure exerted upon the pressure motor and hence control the opening and closing of the fuel valve. Where the opening and closing of the fuel valve is to be controlled by several conditions, such as by the space temperature and the presence or absence of a flame in the pilot burner, it has been the usual custom to provide as many control valves as there are controlling conditions. This is particularly true where the condition responsive devices mechanically actuate the control valves. Such provision of a plurality of control valves materially adds to the expense of the installation and increases the number of moving parts which can get out of order. It has further been the practice where the flow of gas to the pilot is controlled by a thermostat responsive to the presence or absence of a flame in the pilot, or in other words, by a safety pilot, to provide a separate by-pass valve for admitting gas to the pilot and initially starting up the apparatus. With such structures the by-pass valve is held open until the pilot has become sufficiently heated to permit the safety pilot to open the main pilot burner valve.

An object of the present invention is to provide a fuel burner control system of the general type discussed wherein a pressure control valve is provided for regulating the pressure exerted on the pressure motor and a pilot burner valve is provided for controlling the flow of gas to the pilot, in which system a device responsive to one condition, such as the temperature of the space being heated, controls the position of the control valve and in which a second condition responsive device responsive to the presence or absence of a flame in the pilot burner operates to both close the pilot burner valve and to move the control valve to a position wherein the main valve is closed upon the extinguishment of the pilot burner.

A further object of the present invention is to provide a system of the type mentioned in the previous paragraph wherein manually operable means are provided for opening the pilot burner valve without disturbing the position of either the device responsive to the presence or absence of a flame in the pilot burner or the control valve which controls the position of the main valve.

A further object of the present invention is to provide a fuel burner control system of the type in which the flow of fuel to the main burner is controlled by a valve actuated by a pressure motor wherein a single control valve is provided

for regulating the pressure in the pressure motor and consequently the opening and closing of the main valve and wherein said control valve is normally controlled by one condition responsive device and in the event of a critical condition is moved by another condition responsive device to a position wherein the main valve is closed.

Further objects of the present invention will be apparent from a consideration of the accompanying specification, claim and drawing, of which

Figure 1 is a view partly in section of a preferred form of my burner control system and in which

Figure 2 is a detailed view of a portion thereof on an enlarged scale relative to Figure 1.

While my invention is not to be limited to any particular application of my control system, the burner is shown for purposes of illustration as located in a type of unit heater commonly known in the art as a "space heater".

The drawing shows only a fragmentary view of the front wall of this heater, which wall is designated by the reference numeral 10. A portion of a main burner is designated by the reference numeral 11 and is supplied with gas from a main 12 through a conduit 13, the flow through which is controlled by a valve 14. Means 9 are provided for admitting air to the gas supplied to the burner to form a combustible mixture of the proper characteristics.

The valve 14 comprises a valve casing having upper and lower portions 15 and 16, respectively. The lower portion 16 comprises the usual valve inlet 17 and valve outlet 18. Extending between the inlet and outlet portions 17 and 18 is a partition 19 which is apertured at 20 to provide a valve seat upon which is adapted to seat a valve disk 21.

Clamped between the upper and lower portions 15 and 16 of the valve housing is a diaphragm 22, which diaphragm forms a movable wall of a pressure motor, as will be more apparent from the accompanying description. Located on opposite sides of the diaphragm are counterweight members 23 and 24 which are clamped together through a threaded member 25 and clamping nuts 26 and 27. The member 25 serves to connect the valve disk 21 with the diaphragm 22. An aperture 28 extends through both counterweights 23 and 24 and through diaphragm 22. It will readily be seen that the diaphragm 22 divides the valve housing into two chambers 29 and 30 which are separated from each other with the exception of the passage 28, which permits a limited amount of fluid to pass between the two sides of the diaphragm.

A pilot burner 32 is located adjacent the main burner 11 in the customary manner to constitute the igniting means for the burner. This pilot burner is connected to the inlet side of the main

valve 14 through a pipe 33. This connection is controlled by a pilot burner valve 34. This pilot burner valve may be of any suitable construction and comprises a valve disk 35 to which is secured 5 an elongated valve stem 36. Suitable passages 37 are provided in the pilot burner for the admission of air thereto.

A control valve for the main valve 14 is generally designated by the reference numeral 38. 10 This control valve is located in a boss 39 of the valve housing. The valve seat 40 is located at one end of a chamber 46 in the boss 39, which chamber is sealed at its other end by a gland nut 41 which is threaded into the boss 39. A 15 valve head 42 cooperates with the valve seat 40 and is actuated by means of an elongated valve stem 43. The valve seat 40 is in communication with the upper chamber 30 through a passage 44 extending through the upper wall of the upper portion 15 of the valve housing. Extending 20 transversely into boss 39 and communicating with the chamber 46 is a bleed pipe 45, which bleed pipe leads from said valve to a point adjacent the upper portion of the pilot burner 32. It will 25 be readily seen that when the valve 38 is in the closed position as shown no gas can escape from the upper chamber 30 but that when the valve is open, gas can pass out through passage 44, chamber 46 and pipe 45 to the outlet of the pilot burner 30 where it is consumed. Valve 38 accordingly regulates the pressure upon the upper side of the diaphragm 22 and controls the action of the main valve 14 in a manner to be more fully pointed out hereinafter.

35 Located on the front wall 10 of the heater in which the burner 11 is located is a thermostat housing 50, which housing is mounted on a member 51, which serves to space the housing 50 outward from wall 10. Member 51 is provided with 40 apertures 52 to permit free circulation of air between the heater wall 10 and the thermostat housing 50 so as to prevent the thermostat from being directly affected by the heater temperatures.

45 The thermostat 50 comprises a housing formed of a base member 54 and a shell member 55. The shell member 55 is provided with suitable apertures 56 to permit access of the air in the room to the thermostatic element. The thermostatic element is designated by the reference numeral 57 and comprises a more or less conventional looped member of bimetallic material. This bimetallic element 57 is mounted on base 54 through any suitable mounting block 58. Through the upper 50 portion of the outermost leg of bimetallic element 57, a valve stem 43 is extended. At the point where the valve stem 43 extends through bimetallic element 57, portions of the bimetallic element are struck outwardly on each side as 55 designated at 59 and 60. Nuts or other suitable fastening means 61 and 62 serve to secure the valve stem 43 to the bimetal 57 so that any movement of the bimetal 57 is immediately transmitted to valve stem 43 and accordingly to the valve 38 through valve head 42. The struck-out portions 60 59 and 60 being slightly curved serve to form curved bearing surfaces for nuts 61 and 62 and permit a slight pivoting of the valve stem 43 as the bimetallic element changes its angular position. As indicated by a legend on the drawing, the bimetallic element is so arranged that when the temperature rises, the outermost leg thereof to which the valve stem 43 is attached is moved to the left and when the temperature 70 drops, the reverse action takes place.

Mounted upon the pilot burner 32 is a bimetallic element 65, which bimetallic element is secured to the burner through a mounting block 66. A slot 67 is located in the upper portion of the pilot burner adjacent the upper end of the 5 bimetallic element 65. When the pilot burner is lit, flame will issue from the slot 67, which flame will play over the upper end of the bimetallic element 65 and heat the same. As indicated by the legend upon the drawing, the heating of the bimetallic element in this manner causes the right leg of the bimetallic element to move to the right. 10

15 Mounted on the valve stem 36 is a collar 70. Abutting against this collar is a spring 71 which is intended to engage the bimetallic element 65. A pin 72 passes through the valve stem 36 and is designed to limit outward expansion of spring 71. As indicated more clearly in Figure 2, the bimetallic element 65 is provided with an elongated slot 74 which slot is of such shape and so 20 disposed as to permit pin 72 to freely pass therethrough but is sufficiently narrow to prevent spring 71 from passing therethrough. Thus in the position shown, the spring 71 bears against the bimetallic element 65. However, if the bimetallic element 65 by reason of being heated is deflected sufficiently to the right so as to permit spring 71 to engage pin 72, the bimetallic element 65 may move away from spring 71.

25 The pilot burner valve stem 36 extends through 30 the wall 10, member 51, base 54, bimetallic element 57, and shell 55 and has attached in the front end thereof a knob 75 designed for manual actuation of the pilot burner valve stem 36. Also attached to the stem 36 is a collar 77 and located 35 between this collar 77 and the base member 65 is a spring 78 which bears against the collar 77 and serves to bias valve 34 to an open position. Thus upon bimetallic element 65 being deflected sufficiently to the right to move away from engagement with spring 71, spring 78 is effective to move the valve disk 35 away from its seat and to open the pilot burner valve 34 admitting gas to the pilot burner. Moreover, even when the pilot is cold, the pilot valve 34 may be opened by grasping 40 knob 75 and pulling valve stem 36 outwardly against the action of spring 71. This operation will be more fully described in a subsequent paragraph.

45 Connected to the control valve stem 43 is a 50 collar 80 which is similar in function and form to collar 70 of valve stem 36. Likewise, extending through a valve stem is a pin 81 which serves to limit the outward expansion of a spring 82, which spring is shown as bearing against bimetallic element 65. As will be apparent from Figure 2, the construction is substantially the same as that described for valve stem 36 and, as in the previous case, an elongated opening 84 is provided which is of such shape as to permit the 55 pin 81 to move therethrough but to prevent the spring 82 from passing therethrough. Thus as the bimetallic element 65 is deflected sufficiently to the right, it will move away from engagement with spring 82 and leave the valve stem 43 under 60 the sole control of the thermostatic element 57.

65 The operation of my fuel burner control system will now be described. In the positions shown in the drawings, all the burners are extinguished and the main valve, the control valve 70 38 and the pilot burner valve 34 are closed. The main valve is held closed by pressure in the upper chamber 30. This pressure arises by the fact that gas from the underside of diaphragm 22 which is opposed to the fuel line pressure has 75

passed through the aperture 28 into chamber 30 wherefrom it cannot escape by reason of valve 38 being closed. The accumulation of this gas in the upper chamber causes the pressure on the 5 two sides of the diaphragm 22 to be equalized with the result that the valve is moved to closed position by reason of the action of counterweights 23 and 24. The valve disk 21 will remain seated against valve seat 20 until the control 10 valve 38 is opened.

When it is desired to start the burner up, knob 75 is grasped and pulled outwardly so as to open the pilot burner valve 34 against the action of spring 71 as described previously. This permits 15 gas to flow to the pilot burner 32 where it may be ignited as it issues from burner openings 86. Knob 75 is held outwardly until the bimetallic element 65 constituting the safety pilot has become sufficiently heated so as to move away to 20 the right sufficiently to move out of engagement with spring 71. When this has taken place, the biasing action of spring 78 will act to hold valve 34 open after the knob 75 has been released.

At the same time as bimetallic element 65 25 moves away from spring 71, it also moves away from spring 82 permitting the valve stem 43 to be placed under the control of the thermostat 50. If the temperature of the space in which the heater is located is below the desired value, the 30 long leg of bimetallic element 57 will be subjected to a force tending to deflect it sufficiently to the right so that as soon as the control of valve stem 43 by pilot 65 is terminated, the bimetallic element 57 will be operative to move valve stem 43 35 to the right and open control valve 38. As soon as this takes place, the upper chamber 30 is placed into communication with bleed pipe 45 and the gas therein is released through bleed pipe 45 wherein it is consumed by the pilot burner. Due 40 to the fact that the size of the bleed pipe in passage 44 is so much larger than the restricted passage 28, gas will pass out through the bleed pipe much more rapidly than it can pass from the underside of the chamber to the upperside there- 45 of so that no appreciable pressure will exist in the upper chamber 30. This will result in the pressure of the gas on the underside of the dia- phragm being effective to raise the diaphragm and move the valve to open position. This per- 50 mits gas to flow from the supply pipe 12 through pipe 13 to the burner 11 where it is ignited by the flame issuing from pilot burner opening 86.

During the normal operation of the device, the 55 burner will remain in operation until the space temperature has become sufficiently heated by reason of the operation of the burner as to deflect the elongated leg of bimetallic element 57 to the left so as to close control valve 40. The closing of control valve 40 will prevent the escape 60 of gas through bleed pipe 45 and pressure will be built up in the upper chamber which will be effective to close the main valve. The main valve will thus be successfully opened and closed in accordance with the temperature in the space 65 being heated by the main burner.

In the event of the pilot 32 becoming extin- 70 guished in the meantime, or in other words, when the igniting means fails and accordingly is not available for the purpose of igniting the main burner being terminated, the flame issuing from opening 67 will similarly become extinguished and will cause the bimetallic element 65 to assume the position shown in the drawing. In view of the fact that bimetallic element 65 is

constructed of much more rigid material than bimetallic element 57, it is able to overpower the action of bimetallic element 57 and acting through spring 82 is able to close the control valve 38 even though the thermostatic element 57 may be in a position where the control valve 38 would otherwise be open, or in other words, even though the thermostat 50 may be calling for heat. At the same time, the bimetallic element 65 acts through spring 71 to close the pilot 10 burner valve 34. The result is that the supply 15 of gas to both the main burner and pilot burner is cut off. Due to the fact that the pilot responsive thermostat 65 is of much more rigid construction than the main thermostatic element 57, as previously pointed out, it is impossible to 20 reopen the main gas valve until the pilot burner is again lit by operation of the knob 75 in the manner previously described.

It will thus be seen that the control valve 25 38 is controlled by both the thermostatic element 57 and the thermostatic element 65, the control being effected in such a manner that when the thermostatic element 65 which is responsive to the presence or absence of a pilot flame is in 30 its hot position, the valve 38 is controlled solely by thermostat 50. However, when the pilot is extinguished, the thermostatic element 65 is effective to take the control away from thermostat 50 and to close control valve 38 regardless 35 of whether thermostat 50 is calling for heat or not. At the same time the pilot burner valve is extinguished to prevent a flow of gas to the pilot. Moreover, means are provided for opening the pilot burner valve without disturbing 40 the position of the pilot responsive thermostatic element. There is thus avoided the necessity of a plurality of control valves for the main gas valves and at the same time, I avoid the necessity of providing a by-pass for admitting gas to the pilot in starting up.

While I have shown a certain specific embodiment of my invention, it will be understood that this is for purposes of illustration only and that my invention is to be limited only by the scope 45 of the appended claim.

I claim as my invention:

In a fluid fuel burner control system, a main burner, a pilot burner, a main valve controlling the flow of fuel to said main burner, a pressure 50 motor for operating said main valve, means for supplying a pressure fluid to said motor to operate the same, a control valve for controlling the pressure in said motor, said pressure motor being operative when said control valve assumes a first position to move said main valve to open position and when said control valve assumes a second position to move said main valve to closed position, means responsive to a controlling condition for varying the position of 55 said control valve, a pilot burner valve controlling the flow of fuel to said pilot burner, means responsive to the presence of a flame at said pilot burner and directly operative to move said control valve to said second position and to close said pilot burner valve in the absence of a 60 flame at said pilot, said last named means being connected to said pilot burner valve through a strain release connection to permit opening of 65 said pilot burner valve when closed without movement of said last named means and con- sequently without moving of said control valve.
